DISPLAY CONTAINER

Peter D. Korzaan, Teaneck, N.J., assignor to Utility
Printing Company, Carlstadt, N.J., a partnership

Filed Oct. 18, 1962, Ser. No. 72,178

Term of patent 3½ years

(Cl. D58—12.6)

FIG. 1 is a front perspective view of a display container showing my new design, in open condition;

FIG. 2 is a rear perspective view thereof;

FIG. 3 is an enlarged side elevational view thereof;

FIG. 4 is a top perspective view of the container in closed condition; and

FIG. 5 is a bottom plan view thereof.

I claim:

The ornamental design for a display container, substantially as shown.
